UNITED STATES PATENT OFFICE.

FRANK L. HURTT, OF PEORIA, ILLINOIS, ASSIGNOR OF ONE-HALF TO GEORGE LA CROIX, OF PEORIA, ILLINOIS.

MOUTHPIECE FOR MUSICAL INSTRUMENTS.

Application filed May 5, 1920. Serial No. 378,960.

To all whom it may concern:

Be it known that I, FRANK L. HURTT, a citizen of the United States, residing at Peoria, in the county of Peoria and State 5 of Illinois, have invented certain new and useful Improvements in Mouthpieces for Musical Instruments; and I do hereby declare that the following is a full, clear, and exact description of the invention, which 10 will enable others skilled in the art to which it appertains to make and use the same.

This invention has reference to a mouth piece for musical instruments, being directed more particularly to a mouth piece for the 15 so-called brass wind-instruments.

The invention relates to that type of mouth piece having therein a telescopic portion by which in the adjustment thereof the mouth piece may be made to conform to the 20 desires of different users.

Musicians do not all use an instrument in the same way. That is to say, one player will merely place the lips lightly upon the mouth piece while another will place the lips 25 somewhat inside. The same ease of performance cannot be had in both cases since the air movements will be different with the same mouth piece but the adjustment of the telescopic portion will permit the performer to obtain the best results with regard 30 to ease of performing upon his instrument. The construction must be such that there can be no leakage of air outside the device between the parts thereof, since such leakage 35 would naturally interfere with the use of the instrument and the tone produced.

In my type of mouth piece I am enabled to obtain every advantage necessary in a device of this nature.

40 The objects are that of producing an adjustable mouth-piece that can be used with a cornet or an instrument of larger type; a mouth-piece that is proportioned to yield the best possible results; one that has inter- 45 changeable parts for fitting larger or smaller instruments; one that is perfectly tight so as not to leak air; one that can be adjusted to exactness and set permanently and posi-

tively with no parts likely to vibrate and one wherein adjustment of the parts will 50 not change the length of the device such as would change the pitch of the instrument when set for that pitch.

In the appended drawing

Figure 1 is a longitudinal section of my 55 mouth-piece in one of its forms, much enlarged, and

Figure 2 is a similar section of a slightly modified form.

The body of the device is denoted at 1 in 60 Figure 1.

It has an open cavity 2 in the form of a straight bore. The wall opposite the open side of the body is bored and threaded at 3 and receives a threaded tubular stem 4 hav- 65 ing a cylindrical head 5 adapted to slidably fit within the cavity 2.

6 denotes a conically formed cavity whose greatest diameter at the outer end of the head is the same as the diameter of the bore 70 of the cavity 2, the said outer end of the body therefor terminating in a feather edge as shown.

The threaded stem 4 is preferably reduced in diameter at 7, and a sleeve 8 threaded 75 interiorly is adapted to engage the threads of the sleeve as shown, being provided with a knurled flange at its upper end for convenience in turning it. The upper end of said sleeve abuts against the end of the body 80 and serves to positively lock the stem 4 in any desired adjustment. The sleeve is tapered toward its free end adapting it to fit into the instrument, while its bore is straight and receives the straight extremity of the 85 stem 4, the latter having a bore communicating with the bottom of the cavity 6 in a comparatively small opening from which it is gradually expanded until at its end within the sleeve it terminates practically in a 90 feather-edge as shown.

In Figure 2 the body denoted by 9 is the same as in Figure 1, though preferably it is slightly less in length.

The stem 10 is like that described except 95 that it is tapered toward its free end to fit

the instrument in place of the use of the sleeve 8.

11 is a knurled internally threaded nut engaging the threaded stem serving to fix the 5 stem and body relatively.

The adjustment of the stem within the body in either form of the device results in the desired change in accordance with the 10 musician's wishes. The setting up of the sleeve secures the stem and body in rigid relation, the snug fit of the parts preventing escape of air between said parts outside the device, the abutting sleeve 8 in the one case, and the nut 11 in the other particularly serving 15 as a bar to such escape.

The feather-edge with which the head 5 is finished provides a cavity with no abrupt corners or any parts therein to interfere with proper tone production in the instrument, 20 it being noted that the concavity of the walls of said head begins directly at the wall of the body 1. This is important in that the cavity 6 conforms to the accepted form. This, coupled with the constantly expanding 25 bore of the stem also terminating in a feather-edge, gives the very best results.

Either form of the mouth-piece may be used with different sized instruments by making the sleeve 8 in two different sizes as 30 regards its taper, or by having the stem 10 of the form shown in Figure 2 in two sizes. The form in Figure 1 of course is preferred from the fact that merely the sleeve need be removed and replaced by another instead of 35 the necessity of removing the stem 10, Figure 2. An important advantage in my device as to that in Figure 1 is that adjusting the size of the cavity does not change the length overall of the said device. That is to 40 say, it is well known that instruments of the type with which the mouth piece is used are set to the proper pitch by a "tuning slide". Now if the length of the mouth piece is changed by lengthening it the pitch would 45 be made "flat" and by the same rule by a shortening the pitch would be made "sharp."

After having been brought to pitch the instrument would have to be tuned after any 50 adjustment of the mouth piece to suit the requirements of the performer in other types of which I am aware. In my device the pitch having been determined the mouth piece may be adjusted to any degree without change in such pitch.

55 I claim:

1. A mouth piece for the purposes named including a body having a cavity, a tubular externally-tapered member abutting against the body at its end opposite that having the 60 cavity, and a tubular cavitated member adjustable longitudinally within the body and the tapered member, its cavity communicating with that of the body, said tapered member adapted to secure the cavitated member 65 and the body relatively, the body and said

first member in use having a fixed length overall in any adjustment of the cavitated member.

2. A mouth piece of the type named including in its construction a body-portion 70 having a cavity, a member adjustable therein also having a cavity and including an externally threaded tubular part, and an internally threaded, exteriorly tapered sleeve engaging the tubular part adapted to secure 75 the latter, the body, and itself relatively.

3. A mouth piece for the purposes named including a body having a cavity in one end, a tubular cavitated member adjustable 80 within the body and extending from the other end of the same, and a tapered tubular member engaging the extended end of the first named member adapted to secure the same, said body, and itself in rigid relation.

4. A mouth piece for the purposes named including a body having a cavity in one end, a tubular member adjustable within the cavity having a cavity opening into that of said body, and a tubular externally tapered 90 member adapted to abut against the body at its end opposite that having the cavity and engaging the first named member securing it and the body relatively.

5. In a mouth piece for the purposes 95 named, a tubular body having a cavity in one end, a tubular externally tapered member abutting at its large end against the end of the body remote from that having the cavity, the body and member having a fixed length, and a tubular cavitated member adjustable within the body and secured relatively thereto by said externally tapered member.

6. A mouth piece for a brass wind instrument comprising a body having a cavity, a member having an extremity to fit said instrument, the body and member in use on the instrument always having the same relative positions, and a tubular member lying 100 within the body-cavity, itself having a cavity opening into the latter, said tubular member being adjustable longitudinally relatively to the body and the first named member and in use fixed relatively to both.

7. A mouth piece for a brass wind instrument comprising a body having a cavity, a member having an extremity to fit said instrument, the body and member in use on the instrument always having the same relative positions, and a tubular member lying 110 within the body-cavity and the first named member, itself having a cavity opening into the former, said tubular member being adjustable longitudinally within and relatively 115 to both the body and said first named member, all the parts in use being fixed relatively.

8. A mouth-piece for musical instruments including a body-portion having a cylindri- 120

cally formed cavity at one end, a cylindrical member adapted for longitudinal movement therein and having a cavity and a hollow partially threaded stem extending outside the body-portion at the other end of the latter, the diameter of the bore of the said member increasing in size toward its free end terminating in a feather edge, and an externally tapered, partially internally threaded member having a cylindrical bore

within which the end of the first described member has a sliding fit, said tapered member adapted to engage the said first described member and secure it and the body-portion relatively.

15

In testimony whereof I affix my signature in presence of a witness.

FRANK L. HURTT.
